BLAST FURNACE COOLER

Selwyne P. Kinney, Crafton, Pa., assignor to S. P. Kinney Engineers, Inc., Pittsburgh, Pa., a corporation of Pennsylvania

Application April 8, 1944, Serial No. 530,153

3 Claims. (Cl. 266—41)

1
This invention is for blast furnace coolers and relates to a cooler which is protected from damage by molten iron or slag that may result from the burning through of a blow-pipe.

In the conventional blast furnace design, the tuyère through which the blast is introduced into the lower part of the furnace is removably supported within a cooler, this cooler being generally a frusto-conical body having an inwardly tapered central passage therethrough to receive the tuyère. The cooler is connected with a water circulating system. The blow-pipe which supplies air to the tuyère extends axially through the cooler, its inner end terminating at the tuyère and its outer end connecting with the boot-leg that extends upward to the bustle pipe that surrounds the furnace. The tuyères must be quickly replaceable, and to accomplish this, the blow-pipe is disconnected, the tuyère pulled outwardly through the cooler, a new tuyère is inserted and driven into its seat at the forward end of the cooler.

Occasionally in the operation of the furnace, molten iron or slag will back up into the blow-pipe, burn through the blow-pipe, and flow onto the cooler, destroying the cooler. This is apt to occasion a shut down of the furnace for a considerable time to enable the cooler to be replaced.

According to the present invention, the cooler is constructed with removable refractory or other suitable material around a portion of the interior thereof which will protect the cooler when metal or molten slag does burn back through the bustle pipe, but this refractory body will not interfere with the normal insertion or removal of the tuyère. Because the cooler will not be damaged when such a circumstance arises, the blow-pipe can be quickly replaced and a minimum of time will be lost by the shutting down of the furnace for cooler repairs. If the refractory is damaged when such an incident occurs, it can be replaced or repaired while the cooler ring remains in operation.

Also, cooler rings are apt to be damaged from over-heating, due to air becoming trapped in the water circulating passages thereof, and the present invention provides a cooler in which the air may be vented so that it is protected from damage due to this cause.

My invention may be more fully understood by reference to the accompanying drawing, in which:

Fig. 1 represents a section through the wall or bosh of a blast furnace, showing a typical tuyère

and blow-pipe installation with a cooler embodying my invention supporting the tuyère;

Fig. 2 is a rear end view of the cooler embodying my invention;

Fig. 3 is a longitudinal section therethrough; and

Fig. 4 is a transverse section in substantially the plane of line IV—IV of Fig. 3.

In the drawing, 2 designates a portion of the lower part of a blast furnace wall, 3 the cinder bracket thereabout, 4 is the cooler supporting ring, while 5 designates generally the cooler, and 6 is the tuyère at the inner end of the cooler. The blow-pipe for applying air to the tuyère is designated 7, and 8 is the boot-leg on which the blow-pipe is carried, the boot-leg being carried on a connector 9 leading from the bustle pipe 10.

The cooler which is shown in detail in Figs. 2, 3, and 4 comprises a metal body of generally frusto-conical shape, having a conical exterior wall 11, an inner terminal portion 12 providing a seat for the end of the tuyère, and an inner wall 13 spaced from the wall 11, there being an annular chamber 14 between the walls 13 and 11 for the circulating of cooling water through the cooler. The wall 13 forms a central opening through the cooler which is designated 14.

According to the present invention, the lower portion of the wall 13, spanning an arc of about 120° is recessed as indicated at 15 throughout the greater portion of the length of the cooler, the recess terminating at 16 at the inner end of the cooler and having an integral flange 17 formed thereon at the outer end of the cooler. This recess extends about 60° each side of a vertical plane passing longitudinally through the cooler, the side edges of the recess being defined by wall portions 18.

Within the recess is a refractory or other body 19 which is capable of resisting molten iron or slag that might fall upon it, and which will serve as a trough to carry off any such iron or slag. The refractory body 19 preferably comprises refractory brick set in refractory cement and completely filling the recess. The forward or inner end of the refractory body 19 terminates at the inner shoulder 16, and the inner end portion of the cooler beyond the refractory is fully circular to provide the annular support or seat 12 for the tuyère which fits into it.

At numerous places in the outer end face of the cooler are tapped openings designated 20, some of which may be plugged, and one of which may be connected to a water inlet pipe, while another may be connected to a water outlet pipe. In Fig.

2, the two upper openings 20 provide the inlet and outlet passages. In the space 14 between the two openings 20 and extending throughout the full length of the cooler is a partition 21, so that cooling water entering one of the ports 20 must circulate entirely around the cooler to emerge from the other of these openings. According to the present invention, a small hole 22 is cored transversely through the partition. This will serve to allow any air that might otherwise be trapped in the space 14 to escape, thus further protecting the cooler against the effects of heat. While the hole 22 will allow a small amount of water to flow through the partition, the amount which is by-passed in this way is negligible.

Ordinarily the cooler will be cast from copper, but instead of being made from copper, it may be made of other metals, including iron, bronze, and aluminum, or any other metals that may be satisfactory.

The cooler is installed in the furnace the same as a conventional cooler. It has the same exterior shape and dimensions that the conventional cooler has, and it receives the usual standard tuyère. The blow-pipe is connected to the tuyère in the same way, and the cooler does not require any special installation or added equipment for its use. In the event that metal flows back into the blow-pipe allowing slag or metal to escape, the metal will fall onto the refractory 19 from which it can run off, or on which it may collect. After the blow-pipe has been replaced and the furnace is again in operation, or while the blow-pipe is being replaced, any damaged refractory, or refractory to which a mass of metal or slag may be clinging can be taken out and replaced with new refractory.

Thus the invention provides a cooler for supporting the tuyère which, in the event of a blow-pipe burning through with the subsequent escape of metal or slag, repairs can be made quickly and with a minimum loss of time, and without requiring replacement of the cooler as is now frequently necessary where an accident of this kind occurs. Many blast furnaces produce as much as a ton of metal a minute, and the replacement of the cooler may require a shut down for as much as four hours or more. Consequently, the present invention, in avoiding the replacement of coolers due to the burning through of blow-pipes, may effect substantial savings due to the amount of production time that will be saved, in addition to the cost of the cooler itself.

Incidentally the recessing of the bottom of the inner wall of the cooler decreases the cross section of the water circulating space at the bottom of the cooler, thereby tending to increase the velocity of the cooling water where sedimentation is most likely to occur. This is a desirable feature in prolonging the useful life of the cooler.

By forming a recess to receive the refractory, the refractory is contained inside the cooler in

such manner that it will not interfere with the passage of a tuyère into the cooler, or the removal of one tuyère and its replacement by another when it is necessary to change tuyères.

5 While I have specifically illustrated and described one particular embodiment of my invention, it will be understood that various changes and modifications may be made in the construction of the cooler within the contemplation of my invention, and under the scope of the following claims.

I claim as my invention:

15 1. A cooler for holding a blast furnace tuyère comprising a metal body having an inner wall forming an inwardly tapering passageway, the cooler having an annular tuyère supporting seat portion at its inner end, the cooler having a channel-like recess formed in the lower portion of its said inner wall member extending from the tuyère engaging portion of the cooler to the outermost end thereof, and a replaceable body of heat resistant material in the recess, the cooler having an outer wall portion spaced from the inner one and substantially parallel therewith to provide a water circulating space between the two walls.

20 2. A cooler for a blast furnace tuyère comprising a frusto-conical double walled body having a water circulating space between the two walls thereof, a longitudinal baffle extending along the top of said water circulating space between the two walls forming a partition throughout the entire length of the space, said baffle having a small hole therethrough near the larger end of said body, there being a water outlet opening in the structure adjacent one side of the baffle, and means through which water may be introduced into said space.

25 3. A tuyère cooler comprising a double walled frusto-conical body terminating in an inner nose portion and providing between its walls a water-circulating chamber, the inner wall of said body defining a tapering passageway, said inner wall having a radially offset portion rearwardly of the nose and extending across the lower part only thereof for receiving and holding a separate refractory panel, the water-circulating space in the bottom of the cooler under the offset portion being narrowed by the offset to thereby increase the velocity of the cooling water in the bottom of the cooler at the point where sedimentation is otherwise most likely to occur.
